I. Caesar INVENTOR
BY
Sigmund Herzog ATTORNEY

UNITED STATES PATENT OFFICE.

IRVING CAESAR, OF NEW YORK, N. Y.

CANE.

Application filed July 22, 1926. Serial No. 124,226.

The present invention relates to improvements in canes, umbrellas, parasols and the like, and has for its main object to provide a combination cane or the like and portable lighter wherein a frictional sparking device is employed.

Another object of the invention is to so construct the cane and the lighter that the friction disk of the lighter may be actuated by drawing it along the floor or ground, the cane serving in such case as an extension or handle of the lighter, so that the latter may be actuated without stooping down to the floor or ground.

15 A further object of the invention is to provide a combination cane and lighter, the lighter element of which is protected by a detachable element of the cane, which detachable element serves at the same time as 20 the means for extinguishing the flame after the lighter has been used.

A further object of the invention is to provide a contrivance of the character mentioned which is simple in construction, efficient in operation, durable in use and capable of manufacture on a commercial scale, or in other words one which is not so difficult to make as to be beyond the reasonable cost of such a combination.

30 With these and other objects in view, which will more fully appear as the nature of the invention is better understood, the same consists in the combination, arrangement and construction of parts hereinafter 35 described, pointed out in the appended claims and illustrated in the accompanying drawings, it being understood that many changes may be made in the size and proportion of the several parts and details of 40 construction within the scope of the appended claims, without departing from the spirit or sacrificing any of the advantages of the invention.

One of the many possible embodiments 45 of the invention is illustrated in the accompanying drawings, in which:

Figure 1 is an elevation, partly in section, of the lower end of a cane staff having a lighter combined therewith; Fig. 2 is a similar sectional view, the section being taken at right angles to that at which the section shown in Fig. 1 is taken; and Fig. 3 is a section taken on line 3—3 of Fig. 1.

In the drawings, the numeral 10 indicates 55 the lower end of a cane staff. This lower end is hollowed out, as shown at 11, to pro-

vide space for a lighter 12. Adjacent the bottom of the cane are provided exterior screw threads 13, meshing with interior threads of a cap 14, which forms at the same time the tip of the cane.

The lighter comprises a casing 15, preferably, of metal, the said casing being fitted into the hollowed out portion of the cane staff. The bottom face of the casing is disposed flush with the bottom edge of the staff. Into the casing extends, as usual in devices of this type, a wick tube 16, the latter projecting beyond the lower edge of the cane staff, and its wick 17 being saturated with a liquid hydrocarbon, such as gasoline, which is stored within the casing. The lower portion of the casing is reduced in size as shown at 18 and from this reduced portion projects a horizontally disposed post 19, on which is rigidly mounted a vertically extending tube 20, provided at its end, adjacent the wick tube, with lugs 21, between which is rotatably mounted a friction disk 22 on a pivot pin 23. This friction disk is of hard metal, such as steel, and is roughened on its peripheral face, as shown at 24 in Figs. 1 and 3 of the drawings. A bar of sparking material, preferably pyrophoric material, is fitted loosely in the tube 20 and is pressed against the roughened periphery of the friction disk by any suitable means. The friction disk projects below the free end of the wick tube.

The lighter 12 may be removed from the cane staff, for instance when it is intended to replenish the supply of gasoline or when sparking material is to be inserted into the tube 20.

The operation of this device is as follows: When it is desired to use the lighter, the cap 14 is unscrewed from the cane staff and the friction disk 22 brought into engagement with the floor or ground and drawn along such floor or ground so as to rotate the friction disk in the direction of the arrow shown in Fig. 2 of the drawings, whereby a shower of sparks is driven from the pyrophoric material against the exposed portion of the wick, thereby igniting the latter. After using the device, the cap 14 is screwed onto the staff, whereby the flame is extinguished. In making use of the lighter, the cane is used as a handle or as an extension of the said lighter, so that the friction disk may be operated without the user stooping down toward the floor or ground.

It is obvious that, while herein a specific lighter construction has been described, any other may be used without departing from the invention, which lies mainly in the provision of a mechanism which forms an extension of the lighter so that the latter may be used without stooping down toward the floor or ground on which the friction disk of the lighter is to be moved so as to rotate the same.

What I claim is:

A device of the character described comprising a cane staff hollowed out at its lower end and provided with exterior screw-
15 threads adjacent its tip end, a lighter fitted into the hollowed out portion of said staff comprising a casing the lower portion of which is reduced in size, a wick tube on said casing projecting below the lower end of

said cane staff, a horizontally disposed post 20 projecting from the reduced portion of said casing, a vertically extending tube mounted on said post provided at its end adjacent said wick tube with lugs, a friction disk rotatably mounted on said lugs, said friction disk projecting below the free end of said wick tube, a sparking element in said tube in engagement with said friction disk, and a cap having interior threads adapted to mesh with the threads of said cane staff, 30 said cap forming the tip of the cane and serving also to enclose said wick tube and friction disk.

Signed at New York, in the county of New York, and State of New York, this 18th day of May, A. D. 1926.

IRVING CAESAR.
